COMBINED TYPEWRITING AND CARD-PERFORATING MACHINE

Application filed March 27, 1928. Serial No. 285,073.

This invention relates to combined typewriting, calculating and card-punching machines, and especially the carriage-tabulating mechanism. An object of the invention is to provide means for effecting, through operation of a single set of tabulating keys, concomitant denominational tabulating movements of dissimilaneous extents, if necessary, of the separate denomination-determining carriages of combined typewriting and card-punching machines, one carriage having to do with the typing, and the other forming part of the punch-selecting devices. In the joint operation of said machines to produce typed work-sheets and correspondingly punched records of the matter typed, the carriages are to be tabulated to corresponding denominations in corresponding zones, and are accordingly moved to dissimilaneous extents if the work-sheet is divided into zones having a different width or range of denominations than have corresponding zones of a record-card to be punched. For example, an item-zone on the work-sheet may have a sufficient number of denominational columns to permit entry of the total for a large number of items, while the corresponding zone of the card is only wide enough for the largest item, it being the usual practice to punch a separate card for every line of data typed. The carriages may also be tabulated to dissimilaneous extents when skipping of zones is to be effected or where items are to be typed without correspondingly punching the card. Heretofore, zone-tabulation of the perforator-carriage has been effected by pressing the usual zone-tabulating key for the perforator, in addition to pressing a similar key for the typing mechanism. The perforator-carriage was tabulated to the highest denomination in the zone in which an entry was to be made, and then, if necessary, brought to the denomination in which the first significant figure of said entry appeared, by operating, one or more times, a space-key for the perforating mechanism. According to the present invention, the usual single set of denominational tabulating keys adjacent the typewriter-keyboard is employed, and means are provided so that operation of said tabulating keys effects not only a denominational tabulation of the typewriter-carriage, but also effects a corresponding denominational tabulation of the punching-machine carriage. Thus greater efficiency is attained, because the operator need select and operate only one tabulating key, and is relieved of watching the movement of the perforator-carriage for assurance that it indexes columns corresponding to the characters typed.

The invention is herein illustrated as applied to that type of combined typewriting and punching machine, in which each carriage moves step by step under the control of its own feeding device, and in which both feeding devices are jointly controlled by operation of the type-keys to print and to concomitantly actuate corresponding punching devices through the medium of operating trains from said keys to said punching devices. In said type of machine, a punching mechanism carriage serves to shift punch-selecting elements, actuatable by said operating trains, step by step in unison with the letter-feeding movements of the typewriter-carriage, so that holes are always punched in the same denominations as the characters typed. To permit free movement of the perforator-carriage, the operating trains include flexible connecting means between the elements shiftable with said carriage and the fixed key-engaging ends of said trains. There are twelve such punch-selecting trains corresponding to the twelve hole spaces in each of the columns into which the usual card is divided, each column having ten spaces for the digits and two extra spaces for code designations, alphabetical combinations, or other purposes. The typing mechanism may be provided with the usual set of denominational stops, each controlled by its own key, and, for co-operation therewith to serve the perforator-carriage, the invention provides a similar set of denominational stops for the perforator-carriage.

A feature of the invention resides in the provision of means enabling the employment of the punch-selecting trains as operating connections from the typewriter-tabulating keys to the perforator-denominational stops.

This is of particular advantage in the type of machine herein illustrated, in which the carriage-feeding escapement-mechanism is of such nature that the set of perforator-denominational tabulating stops is best mounted on the perforator-carriage. By employing for the perforator-carriage stops the same set of operating trains as serve for selecting the punches, the perforator-carriage 10 is not encumbered by additional trains of connections which would otherwise be necessary to actuate the perforator tabulating stops thereon. Besides this advantage there are also the advantages resulting from not 15 increasing the number of connections between the typewriting and perforating mechanisms.

An additional operating train, actuated by a universal bar at the operation of any type-writer-tabulating key, may serve to actuate novel means herein provided for rendering the operating trains effective upon the perforator-denominational stops, and ineffective upon the punch-selecting elements, said 20 trains being arranged so as to be actuatable by the type-keys or by the tabulating keys. Said novel means are so arranged that, as a tabulating key is pressed, the switching of the operating trains precedes the operation of 25 said trains, so that the movement of the selected denominational stop into effective position is assured. Means are provided whereby, upon conclusion of said movement of the denominational stop, the perforator-carriage is released from the control of its 30 feeding or escapement device to initiate a tabulating movement of said carriage. Said universal member controlling the switching of the operating trains may be the same member 35 that serves to release the typewriter-carriage for a tabulating movement, both carriages being driven in these movements by individual motors.

Means, including zone-determining stops 40 settable along a stationary member, co-operate with the denominational stops mounted on the perforator-carriage to effect termination of the tabulating movement of said perforator-carriage as it reaches, in successive 45 zones, the denominational position corresponding to whichever tabulating key is operated, the typewriter-carriage being similarly arrested by means of its own set of stops.

On account of the limited room afforded by a card for hole-space columns, successive item-zones into which the card is divided are necessarily directly adjacent to one another. The perforator-carriage in the usual punch-selecting operation escapes and moves one 50 step or column ahead, as each character is typed and the corresponding punch is selected. This escape may be effected by means of the usual escapement-controlling universal 55 bar operable by any one of the previously-

mentioned punch-selecting elements. If tabulating is to be successively effected in adjacent zones, the perforator-carriage must not be permitted to escape after serving the last or units column of a zone. Otherwise, should the carriage thus escape, the stop for the highest denomination of the succeeding zone will have passed the zone-stop for said latter zone, and, should a tabulating key for said highest denomination then be pressed, the zone would be skipped. Means, preferably effective upon the aforesaid escapement-controlling universal bar, are accordingly provided to prevent escape of the perforator-carriage, after it has served the last or unit 70 column of a zone, said means automatically becoming set to render said universal bar ineffective as the carriage escapes to said last column after serving the preceding column. Other means, effective upon said escape-preventing means, are provided to restore the latter means upon pressing a tabulating key for the succeeding zone, and to thereby render said escapement-controlling universal 75 bar effective again. 80

By providing means for preventing escape of the perforator-carriage, the operator is further relieved of watching said carriage, and the typewriter-carriage may be denominational tabulated irrespective of whether the perforator-carriage is already at the highest denomination of the corresponding zone. Thus the perforator-mechanism may be in any desired position with respect to the typewriter, as no consideration need be given 90 to placing the perforator so that its carriage is within observing range of the operator. This is particularly feasible with the type of combined typewriting and punching machines herein shown in which the aforesaid operating trains from the type-keys to the punch-selecting elements are electrically actuated, the only connection between the two machines being an electric cable for the circuits controlling the operation of said trains. 100

The denominational stops for the perforator-carriage may be in the form of bars arranged transversely of the direction of movement of the perforator-carriage, and mounted on said carriage for movement endwise to enable the end of a selected bar or stop to engage the stationary zone-stops. The punch-selecting elements on the perforator-carriage for the type of machines herein shown have extensions for receiving actuating impulses or thrusts from the operating trains, said thrusts being in the direction of carriage movement. Members having portions movable in the direction of said thrusts may serve to translate said thrusts into corresponding movements of the transversely-arranged denominational stops, and, to this end, said portions may be adjacent the extensions of the punch-selecting elements, so that said operating trains may be conveniently 110 115 120 125 130

ently switched from operative connection with said punch-selecting elements to operative connection with the members actuating the denominational stops, and vice versa.

5 For thus switching the operating trains, there may be employed a set of interponents or switch elements having ends always in operative connection with said operating trains. Opposite ends thereof may engage 10 either the punch-selecting elements or the tabulating stop-controlling members depending on the position of said interponents or said switch elements.

15 Latching means are provided to hold a selected denominational tabulating stop of the perforator-carriage in effective position after being moved into position by pressing a tabulating key, and are so arranged that the engagement of a denominational stop

20 with a zone-stop, besides effecting termination of the tabulating movement, automatically effects release of the denominational stop and its restoration to normal ineffective position. The aforesaid interponents or

25 switch elements for the operating trains may be similarly latched in their denominational stop-selecting positions until the termination of the perforator-carriage tabulating movement, their return to normal position also 30 being effected as a result of the engagement of a denominational stop with a zone-stop. In their normal positions, said interponents or switch elements may be effective to engage the punch-selecting elements. In the type

35 of perforating mechanism to which the invention is herein illustratively applied, termination of the tabulating movement of the perforator-carriage is effected by restoring the effectiveness of the perforator-carriage

40 escapement-device to hold said carriage, said carriage having been released from said device, as previously stated, to initiate a tabulating movement, and said release being maintained by means of a latching device.

45 Inasmuch as said release is effected upon selection of a denominational tabulating stop by pressing a tabulating key, the means whereby latching of said escapement-device is effected are so arranged to permit termination of the tabulating movement irrespective of whether the operator keeps pressing the tabulating key after the selection of a denominational stop and the release of the perforator-carriage are effected. This last 50 feature assures proper arrest of short tabulating movements of the perforator-carriage.

55 Other features and advantages will hereinafter appear.

60 In the accompanying drawings, Figure 1 is a front elevation of the punching machine carriage, showing how the denominational stops, punch-selecting elements, operating trains and related devices may be arranged thereon.

65 Figure 2 shows how the punching machine

may be connected to the typewriting machine by an electric cable for the circuits controlling the electrical operation of the means whereby joint operation of said machines is effected.

70 Figure 3 is a top plan view of the punching machine carriage indicating the parts shown in Figure 1.

75 Figure 4 is a diagram, showing how the typewriter-tabulating keys by means of a universal bar may effect shifting of the shiftable interponents or switch elements that switch the operating trains from the punch-selecting elements to the perforator-stop actuating members.

80 Figure 5 is a cross-sectional elevation, showing the parts indicated in Figures 1 and 3.

85 Figure 6 is a perspective view, showing the operated position of the means whereby the escapement-mechanism of the perforator-carriage is rendered ineffective when said carriage is in the last column or units position for any zone.

90 Figure 7 is a view, showing how the zone-stop engages and actuates a member forming part of the escapement-silencing means as the perforator-carriage reaches a units or last column position of any zone.

95 Figure 8 is a view of the punching machine carriage, showing, in perspective, the various parts indicated in Figures 1, 3, and 5.

100 Figure 9 is a view of portion of a card, such as is produced in the punching machine.

105 Figure 10 is an operated view indicating means whereby the engagement of a denominational stop by a zone-stop may effect restoration of the denominational stop to its ineffective position.

110 Figure 11 is a view, showing, in perspective, the operated positions of the parts whereby the perforator-carriage is released from its escapement of feeding device upon the selection of a denominational tabulating stop.

115 Figure 12 shows how means for releasing the perforator-carriage from its escapement-mechanism are arranged to permit termination of the tabulating movement irrespective of whether the operator holds a tabulating key longer than the duration of said tabulating movement.

120 Figure 13 indicates the position of a zone-stop relative to the perforator-carriage denominational stops, as said carriage is held by its feeding mechanism within the zone for said zone-stop.

125 Figure 14 is a perspective diagram, showing the operating connections from the type-printing and tabulating keys to the perforator-carriage, and also showing the circuits and the means included in said circuits for the electrical operation of said trains.

130 Figure 2, exemplifying a type of combined typing and card-punching machine to which

the invention may be applied, indicates the well-known Underwood-Hanson bookkeeping machine, generally designated by the number 20, coupled to an electrically-controlled punching machine for joint operation.

3 Said card-punching machine, generally designated by the number 21, may be of the type indicated in the patent to William W. Lasker, No. 1,287,706, dated December 17, 1918.

10 A letter-feeding carriage 22 of the Underwood typewriter, included in said bookkeeping machine, advances step by step by means of the usual escapement-mechanism 23, actuated by operation of type-keys 24, and is

15 drawn by the usual spring-motor 25. The usual Underwood denominational tabulating mechanism for said carriage includes a set of denominational keys 26 attached to key-levers 27, Figure 14, for moving denominational stops 28 at the rear of the typewriter into the path of zone-stops 36, settable along a bar 29 attached to the carriage 22.

20 The card-punching mechanism will be briefly described. Said punching mechanism 25 includes a nest of punches 30 (Figure 5) and a die-plate 31 therefor, said punches being retained in a frame including a plate 32 and the die-plate 31. A gap 33 separating said plates may receive a card 34 to be punched. The 25 nest of punches is arranged in numerous denominational columns of twelve punches each, ten punches for the digits and two extra punches serving various purposes as previously mentioned.

25 Figure 5, which is a cross-sectional elevation through the nest of punches, indicates one of said punch-columns. Over the nest of punches and aligned endwise thereof, is a similar nest of the usual punch-indexing pins 35, each movable downwardly from normal position to oppose upward movement of a corresponding punch, and thereby effect perforation of the card, said card, when punching is to be effected, being moved upwardly with the 30 punches in the usual manner during a punching-machine-operating cycle. The usual denomination indexing punching-machine carriage, generally designated by the number 37, serves to depress the index pins 35 column by column, and, to this end, carries a set of rods 38 movable endwise and downwardly in a pin-setting direction, there being one of said rods 38 for every punch in a column. Each rod 38 is attached to a bell-crank 39 having an arm 40 extending upwardly for receiving actuating impulses, as indicated in Figure 1.

35 The usual escapement or feeding device for the punching-machine carriage 37 serves to advance said carriage to the next step or column, as soon as the preceding column has been served, said carriage advancing from left to right along the usual guide-rails 41. Said feeding device includes an escapement-wheel 42, rotatably mounted on said carriage 37. Said escapement-wheel under the influ-

ence of the usual spring-motor 43 reacts against a holding dog 44, and also reacts through the medium of a pinion 45 against a stationary escapement-rack 46. Escapement of the carriage is effected in the usual manner by oscillating the holding dog 44 together with a stepping dog 56.

40 A spring-pressed universal member 57 actuatable by operation of any one of the bell-crank 39 serves to oscillate the dogs 44 and 56. Said universal member 57, in the form of a bail having side arms fulcrumed on the perforator-carriage at 47, has an extension 48 on one of said arms for oscillating said dogs. To this end said extension carries at its lower end, as best seen in Figure 8, a pin 49 co-operating with a cam-slot 50 formed at the end of an arm 51 connected to the dog 56 by a shaft 52 to which said dog 56 and arm 51 are secured.

45 The perforator-carriage may be tabulated by withdrawing and latching the dog 44 to release the carriage, and terminating said release and ensuing tabulating movement by causing the dog to re-engage the escapement wheel as the carriage reaches a predetermined position. To this end the dog 44 is not fixedly attached to the dog 56, as in ordinary escapement-mechanism devices, but is loosely mounted for independent movement on the shaft 52. An arm 54 of the dog 44 engages a pin 53 of the dog 56, so that a spring 55 pulling on the dog 44 may serve to yieldably connect said dogs to oscillate together during the 50 step-by-step feeding of the carriage.

55 For withdrawing the dog 44 and latching it, there may be provided a spring-pressed lever 60 fulcrumed on the punching machine carriage at 61. The lever 60 may lift the dog 44 by means of pins 62 and 63 projecting respectively from said lever and dog. A spring-pressed latch 64 pivotally mounted at the end of said lever, as indicated, may serve to hold the latter, together with the dog 44, in carriage releasing position, said latch having a portion 65 which may be caught on a projection 66 of the punching machine carriage and readily releasable therefrom to terminate a tabulating movement. A spring 77 may pull upon said lever 60 to retract it.

60 A set of selectively-movable denominational tabulating stops 67 for the punching-machine carriage may be normally in ineffective position. Said denominational stops 67, preferably in the form of bars, are in the illustrated form of the invention, mounted on the carriage 37 and extend transversely of the direction of carriage-motion, so that an end of a bar or stop selected by reason of its endwise displacement may, for terminating a tabulating movement, co-operate with zone-stops 68 settable in zone-determining positions along a stationary bar 69, secured to the punching-machine framework 70.

The denominational stops 67 may be retained in guides 71, secured to the punching-machine carriage, said guides having stop-receiving slots 72 spaced according to the spacing of the punch or card columns. A suitable spring 73 may serve to retract a selected stop from the effective position in which it may be latched, the stop being thus latched so that a stop-selecting impulse may not be sustained. Each stop 67 may have a latching step 74, which, as said stop is displaced forwardly for selection, may be caught against one of the guides 71, as indicated in Figure 11. In ineffective position, each stop may, under the influence of the spring 73, react against a fixed plate 75, and may have a step 76 to bear upon said plate.

As the punching-machine carriage advances in a tabulating movement, the selected denominational stop will encounter one of the zone-stops, and, as a result, there may be caused displacement of the selected denominational stop, and which displacement may be utilized to terminate the tabulating movement. To effect such displacement, the forward ends of the denominational stops may have camming surfaces 78 to coact with similar camming surfaces 79 of the zone-stops, for effecting upward displacement of the forward end of a selected denominational stop as it encounters a zone-stop. Said upward displacement may serve to actuate a bail 81, the operation of which, through suitable means to be described, is effective to kick off the latch 64, and thereby release the dog 44 and arrest the tabulating movement of the punching-machine carriage, said dog 44 having, by means not yet described, been withdrawn from the escapement-wheel and latched to initiate a tabulating movement concomitantly with the selection of the denominational stop.

Operating trains connecting the type-writing mechanism to the punching machine are preferably electrically actuated. Said trains may serve not only to connect the type-keys 24 with the punch-indexing bell-cranks 39 substantially in the manner heretofore practiced, but may also, according to the present invention, serve as operating trains, whereby operation of the typewriter-tabulating keys 26 effects selection of corresponding denominational stops 67 for consequent tabulation of the punching-machine carriage.

The operating trains are generally designated by the number 83, and each train includes an electromagnet, preferably in the form of a solenoid 84 having a core or plunger 85 which may be caused to move from normal position by energizing the solenoid with current from a suitable source 86 to which each solenoid is connected through a normally open but closable circuit. For transmitting the movements or thrusts

of the solenoid-plungers 85 to suitable points on the punching-machine carriage where said thrusts may be utilized to actuate the punch-selecting devices or the denominational stops and carriage-releasing devices, there may be employed flexible push wires 82. Each push wire may be connected at one end to one of the plungers 85, and may have the other end connected to one of a row of rods 87, each mounted for endwise movement in a block 88. Said block may be secured to the punching-machine carriage, which, nevertheless, may move freely by reason of the flexibility of the push wires and flexible sheaths 89 which retain said push wires. Each of the sheaths 89 may have one end secured to the block 88, and the other end secured to a mounting (not shown) that supports the solenoids. The solenoids are preferably mounted so that their plungers are thrust upwardly from normal positions, the return to normal positions with consequent retraction of the push wires being preferably effected by gravity acting upon said plungers.

To simplify the illustration of the invention, the ten numeral-keys only are shown as being effective to actuate the operating trains 83. As seen in Figure 14, there may be below the forward end portion of each type-key-lever 91 a normally-open contact switch 92, which may be closed as said lever is depressed to actuate a type of the usual set of types conventionally represented at 102. The solenoids of a corresponding operating train may thus be caused to be energized every time a type-key is operated.

As the operating trains 83 are to serve also for the selection of the denominational tabulating stops 67 and consequent tabulation of the punching-machine carriage through operation of the typewriter tabulating keys 26, there may be provided for each tabulating key a normally-open contact-switch 94, which may be below and therefore closable by operation of the lever 27 of said each tabulating key. The operating trains 83 being thus actuable either through operation of the type-printing keys or through operation of the tabulating keys, means, which will now be described, are provided for delivering the thrusts of said trains to either the punch-selecting devices or to the punching-machine carriage-tabulating devices, depending upon which kind of key is operated.

For switching the operating trains from one set of devices to the other, there may be provided a set of switchable interponents preferably in the form of spring-pressed rods or plungers 97, Figure 8, mounted on the punching-machine carriage opposite the thrust-delivering rods 87 of the operating trains, and arranged in a row similar to the arrangement of said rods 87, so that a broad head 98 at one end of each plunger 97 is opposite a corresponding thrust-delivering rod

87. A suitably-limited sidewise displacement of all the rods 97 may serve to align the other ends thereof either with the upwardly-extending arms 40 of the punch-selecting bell-cranks 39, or with members forming part of the tabulating devices and which latter members will be presently described. For effecting sidewise displacement of the switching plungers 97 they may be retained in a shiftable switching carriage 99, which may run upon a guide 100, forming part of the punching-machine carriage, as indicated in Figure 8. Said switching carriage 99 may have rolls 101 bearing upon said guide 100, and may be normally in such position that the switching plungers 97 are aligned with the arms 40 of the punch-selecting bell-cranks. Thus the operating trains 83 may be normally effective to actuate the punch-selecting devices.

The board heads 98 of the train-switching plungers 97 serve to keep said plungers always in operative connection with their respective operating trains 83, the movement of the switching carriage 99 being limited to about the distance spanning an arm 40 and the adjoining tabulator-actuating rod-ends 105.

For shifting the switching carriage 99 to thereby connect the operating trains with the tabulator-actuating rods 104, there may be employed an additional operating train 116, including a thrust-delivering rod 117, Figure 8, co-operating with a bell-crank 118, pivoted on the punching-machine carriage 37 at 119. Said operating train 116 has its own operating solenoid 120, including a movable plunger 121 connected to the thrust-delivering rod 117 on the punching-machine carriage by a flexible push wire 122. For energizing said switching carriage, solenoid 120 upon operation of any tabulating key 26, there may be provided a universal member 125, Figure 14, which may be the usual member that serves to release the typewriter-carriage 22 for a tabulating movement upon operation of any typewriter-tabulating key 26, said release being effected by the usual means, conventionally represented at 106, actuated by said universal member. The latter is, as usual, directly actuated by an upward movement of any typewriter-denominational stop 28. A shaft 126, to which said universal member is secured for oscillation, may have an arm 127 secured thereto, which may co-operate with a suitably-mounted bell-crank 128, to effect closing of normally-open switch-contacts 129, to close the circuit for, and consequently energize, the switching-carriage solenoid 120. By closing the switch-contacts 129, by operation of any tabulating key 26, the switching carriage 99 may thus be caused to be moved to bring the train-switching plungers 97 into alignment with the tabulator-actuating rods 104. The switching movement thus imparted to said carriage 99 may be limited by a fixed stop 131. Said carriage 99 is preferably retained in tabulating position by means of a latch-arm 132 pivoted thereon, the end of which, in bearing against a fixed stop 133, may serve to establish the alignment of the switching plungers 97 with the tabulating-actuating rods 104, as indicated in Figure 11.

The switching-carriage solenoid 120 may be so wound that its self-induction is less than that of any of the solenoids 84, in order that the shifting of the switching carriage 99 may properly precede a thrust of a plunger 97. In preference, however, for securing proper sequence of operation, there may be employed a normally-open contact-switch 137, which may be so disposed as to be closed by the switching carriage 99 as it reaches its tabulating position. Said switch-contacts 137

137 may be in a common lead 138, Figure 14, of the tabulating-key contacts 94. Thus it will be seen that until the carriage 99 is in tabulating position and has closed the contacts 137, the tabulating-key contacts 94 will not be effected to energize the solenoids 84, thus assuring a proper sequence of the movement of the switching carriage 99 and thrust of the plungers 97. As already stated, the 10 switching carriage 99 is normally in punch-selecting position, and may be held by a spring 140 against a fixed stop 141 which establishes said position. Said spring 140 also holds, through the medium of the latch-arm 15 132, the carriage 99 against the fixed stop 133 in tabulating position.

Release of the punching-machine carriage to initiate a tabulating movement concomitantly with a selection of a tabulating stop 20 67 is preferably effected by utilizing the end-wise displacement of any tabulator-actuating rod 104. To this end, there may be employed a universal member or bail 142, which may span the outer ends of the tabulator-25 actuating rods 104, as indicated in Figure 8, and have side arms 143 secured to a shaft 144, which may be journaled in the punching-machine carriage structure. A spring 145 may retract the bail 142 in a direction counter to the thrust it receives from any of the tabulator-actuating rods 104, and thus serve to hold said bail in normal position.

The displacement which the bail 142 receives, as a denominational stop is selected, 35 may be utilized to withdraw the escapement-dog 44 from the escapement-wheel 42, to initiate a tabulating movement. To this end there may be secured to the bail-shaft 144 an arm 147, which may carry a pivoted hook 148, capable of engaging and lifting the forward portion of the dog-lifting lever 60. Said hook 148 may catch in an opening 149 on said lever 60 and may be so mounted that it escapes from said opening just after the 40 lever 60 has been lifted sufficiently to enable the lever-latch 64 to be caught over the projection 66. Figure 12 shows how the hook 148 may thus escape from said lever. It will be seen that this escape may be effected by 45 limiting the clockwise movement of said hook relative to the arm 147 on which said hook is mounted, so that, in lifting the lever, the lever-engaging portion of the hook is caused to recede from said lever, said portion turning in fact about the axis of the bail-shaft 144. Stopping means for thus limiting the 50 movement of the pivotally-mounted hook 148 relative to the arm 147, may consist of a pin 150 projecting from said arm and 55 engaging a portion 151 on the hook. Figure 1 indicates the relative normal positions of the dog-lifting lever 60 and the lifting arm and hook 147-148 therefor. In said normal positions the hook-stopping pin 150 and portion 151 may be in engagement, and the lift-

ing edge of the hook may be within the lever-opening 149. Inasmuch as the hook 148 and the parts which serve to raise it are to be permitted to return to normal positions after the withdrawal of the dog 44 has been effected 70 by lifting and latching the lever 60, there may be provided a spring 153 effective to insure re-engagement of the lifting edge of the hook with the lever 60, as said lever reassumes its normal position at the end of a tabulating 75 movement. Under the influence of said spring 153 the point of the hook may bear against the side of said lever 60, while said lever is latched to sustain the withdrawal of the dog 44 and the hook-raising arm 147 has 80 reassumed its normal position; in this case there would be a corresponding separation of the hook-stopping pin 150 and portion 151. Then, upon the dog-lifting lever-latch being 85 kicked off to terminate a tabulating movement of the carriage 37, the hook 148 under the influence of its spring 153 would snap into the opening 149 of said lever as the dog 44 and said lever reassumes their normal positions. 90

The advantage of providing dog-lifting means, that leave the dog free to be restored, substantially as soon as the latch 64 has been caught, is apparent in short tabulating runs of the punching-machine carriage, which may 95 be completed before the operator releases the tabulating key. It will be understood that in the operation of the Underwood denominational-tabulating mechanism, the operator holds the tabulating key 26 until the typewriter-carriage is blocked by the particular denominational stop 28 elevated by said key. Upon the typewriter-carriage being 100 so stopped, the operator may release the key. If no means were provided for permitting immediate termination of the tabulating movement of the punching-machine carriage, it is probable that in tabulating for short runs, said carriage would overstep and exceed its intended movement. Heretofore, as 105 practiced in ordinary zone-tabulation of the punching-machine carriage, means were operated, whereby the escapement-dog 56 was caused to be interposed against the escapement-wheel 42 and kept so interposed while 110 the dog 44 was being withdrawn and latched. The tabulating movement was then finally brought under way as the tabulating key was released and the dog 56 thereby withdrawn. Inasmuch as it is desired that the operator 115 need not watch the punching-machine carriage, it is provided that the punching-machine carriage may begin to move as soon as the tabulating key is depressed, so that the operator need not wait and observe the termination of a punching-machine carriage-tabulating movement, which otherwise would follow a similar movement of the typewriter-carriage if said punching-machine carriage 120 were held by the dog 56 until the tabulating 125 movement was completed. 130

key was released. By providing that the dog-withdrawing means may permit immediate restoration of said dog, as described, the feasibility of moving both carriages simultaneously for tabulation is assured.

The means whereby a tabulating movement of the punching-machine carriage is terminated upon the encounter of a selected denominational stop 67 with a stationary zone-stop 68 will now be described. As already stated, said encounter causes the forward end of the selected denominational stop to be displaced upwardly, said upward displacement serving to actuate the bail 81 which spans all the denominational stops 67 so as to be actuatable by any one of them. Said bail may for oscillation be secured to a shaft 154, journaled in the punching-machine-carriage structure, and may have a downwardly extending arm 155, to which may be attached a spring 156 to retract the bail and hold it in its normal position. A link 157, Figures 5 and 10, connects said arm to an arm 158 of a bail 159 underlying the rear end portions of the denominational stops 67, said latter bail being secured for oscillation to a shaft 160 journaled in the punching-machine-carriage structure. By means of said latter bail 159, the rearward end of a selected denominational stop is raised and thereby released for retraction by the spring 73 as said selected stop encounters a zone-stop, said release being effected as the latching step 74 of the stop 67 escapes from its holding edge. A spring 161 for each stop 67 may draw its rear end portion downwardly to insure proper latching.

Displacement of the bail 81 by the encounter of the selected denominational stop with a zone-stop, may be utilized to kick off the latch 64 and effect restoration of the escapement-dog 44 to thereby terminate a tabulating movement. To this end, there may be loosely mounted on the universal bail-shaft 144 an arm 162 which may be vibrated to kick off the latch 64. Said arm 162 may be joined to an arm 163 to form a lever actuatable by the bail 81, said latter arm being connected to said bail by a link 164. For convenient disposition of the two arms 162 and 163, they may be joined by a yoke 165.

Concomitantly with the restoration of the escapement-dog 44 and the selected denominational stop, there is effected through displacement of the bail 81 a restoration of the switching carriage 99 to its normal position. An arm 166, secured to the shaft 154 of said bail, may kick off the latch-arm 132 which holds said switching carriage in its tabulating position. As said latch-arm 132 is kicked off the carriage 99 is retracted by its spring 140 against the stop 141. Figure 12 shows the bail 81 partially actuated through the encounter of a selected denominational stop 67 with a zone-stop 68, and shows how the

dog-holding latch 64 is about to be kicked off by a tab 167 of the arm 162, the kick-off being finally effected as the selected denominational stop 67 becomes fully displaced in passing over the zone-stop 68. In normal 70 denomination-indexing position of the punching-machine carriage, as determined by the teeth of the escapement-wheel 42, a zone-stop may be between adjoining denominational stops, as indicated in Figure 13. 75 Figure 12 also shows how the dog-lifting hook 148 is free of the dog-lifting lever 60 to permit restoration of the dog 44 while the tabulator-actuating rod 104 and the universal member 142 are still displaced by sustained 80 tabulating-key pressure.

It will be understood that the denominational stops 67 in their retracted positions cannot encounter the zone-stops 68, and thus the denominational stops 67 following a selected zone-stop as seen in Figure 13 cannot interfere with further movement of the punching-machine carriage.

As previously stated, the punching-machine carriage must not, in the process of advancing step by step for punch selection, be permitted to escape after serving the last or units column of a zone. Otherwise should the carriage thus escape, the denominational stop 67 for the highest denomination of an 85 immediately succeeding zone will have passed the zone-stop for said latter zone, and should a tabulating key for said highest denomination then be pressed the zone will be skipped. Means for preventing escape of the punching-machine carriage after it serves the last or units column of a zone may displace the escapement-actuating universal bar 57 which is actuatable by any one of the several punch-selecting bell-crank 89, said displacement of 100 said universal bar 57 being utilized to render it incapable of actuating the arm 51 whereby the escapement-dogs 44 and 56 are vibrated. To this end the pin 49, which cooperates with the cam-slot 50 of said arm 51 to vibrate 105 said escapement-dogs and which, as already stated, projects from the arm 48 of said universal bar 57, may be cone-shaped. In normal dog-vibrating position of said universal bar 57, the large end 95 of said cone-shaped 110 pin, being on account of its size, in full engagement with the cam-slot 50, is enabled to co-operate with said slot effectively. Upon an endwise forward displacement of said pin 49, effected by a corresponding displacement 115 of the universal bar 57, see Figure 6, the smaller portion 96 of said cone-shaped pin 49 is brought within the cam-slot 50 and being, on account of its smaller size, incapable 120 of fully engaging the cam-slot 50, the pin 49 and therefore the universal bar 57 are ineffective to oscillate dogs 44 and 56. A spring 59, applied to the arm 51, may be employed to prevent the dog 56 falling toward the es- 125

130

capement-wheel 42 as the pin 49 is displaced forwardly.

For displacing the universal member 57 as the carriage reaches a last or units column 5 position in a zone, there may be provided a train having at one end a bell-crank 170 pivoted upon the punching-machine-carriage structure and operable by a zone-stop, as will be described. At the other end of said train 10 there may be an arm 171 having a forked end 172 embracing a side arm 173 of the universal bar 57, so that vibration of said arm 171 may effect endwise displacement of the bail 57 and consequently of its escapement-actuating 15 pin 49. Connecting said bell-crank 170 and arm 171, which for convenient operation may be disposed as shown, are a link 174 and an arm 175 secured to a shaft 176 to which the forked arm 171 is also secured. Said shaft 20 176 may be journaled in a bracket 177 forming part of the punching-machine structure. A spring 178 may serve to hold the universal bar 57 and its shifting train in normal position. As seen in Figures 6 and 7, a spring- 25 pressed pawl 179 on the bell-crank 170 is encountered by a zone-stop 68 as the carriage reaches a last or units column of a zone, thereby effecting displacement of the bell-crank 170, and a consequent displacement of the 30 pin 49 to render the punching-machine-carriage escapement-mechanism inoperative. Restoration of the effectiveness of said escapement-mechanism is effected upon pressing a tabulating key, the punching-machine 35 carriage with its bell-crank 170 and its pawl 179 in the ensuing tabulating movement passing beyond the zone-stop which caused the displacement of said bell-crank 170 and thus permitting the spring 178 to restore the universal bar 57 and its pin 49, together with the shifting train upon which said spring 40 pulls, to normal position.

In the return movement of the punching-machine-carriage the spring-pressed pawl 45 179 on the bell-crank 170 is idly tipped as it passes over the zone stops in said return movement. As shown in Figure 7, the bell-crank 170 is so positioned on the punching-machine-carriage 37 in relation to the denominational stops 67 that it is displaced by a 50 zone-stop 68 when said carriage is in a units or last column position of the zone established by said zone-stop. Said Figure 7 also serves to illustrate how the zone-stop 68, at 55 the right of said Figure 7, would pass under the last denominational stop 67 and thereby render the latter ineffective, if the carriage were permitted to escape after serving the units column of the zone established by said 60 zone-stop at the left of said Figure 7. It will be understood that said zone-stop 68 at the right of Figure 7 is set on the stationary bar 69 for a zone of nine denominational places.

Figure 9 shows a portion of a record card 65 such as produced by the punching mechanism

herein described and illustrates how the zones into which the card is divided are necessarily directly adjacent to one another; that is to say, there are in order to utilize the full area of the card, no idle spaces marking the divisions between the several zones. 70

The denominational stop-guides 71 and the tabulator-actuating-rod guides 107 may form a box-like structure which may be secured to a frame in which the punch-selecting bell- 75 cranks are mounted. In the sides of said box-like structure thus formed, the previously mentioned shafts 144, 154 and 160 may be conveniently journaled. A tab 181 may pivotally support the bell-crank 170. 80

Also attached to the punch-selecting bell-crank frame 180, there may be a fixture 182 that may serve to support the push-wire block 88, and may include the guide 100 for the switching carriage 99. The bell-crank 85 118 for shifting said switching carriage may have its pivot on a plate 183, which may be secured to said block 88. A portion of said fixture 182 may as indicated also serve as the stop 133 against which the end of the carriage latching arm 132 may react. 90

The operation of the invention and parts related thereto may be summarized as follows: The switching carriage 99 is, as already stated, normally in such position that 95 the switching plungers 97 are aligned with the arms 40 of the punch-selecting bell-cranks 39. As a type-key 24 is operated to print, the corresponding contact switch 92 is closed, thereby energizing the corresponding solenoid 84, so that its push-wire 82, through the medium of the thrust-delivering rod 87 and corresponding plunger 97, delivers a thrust or impulse to the arm 40 of the corresponding punch-selecting bell-crank. The impulse which the bell-crank thus receives is utilized to depress the pin setting rod 38, and consequently depress and latch, by means of the usual latch-plate 169, the punch-indexing-pin 35 for the punch 100 corresponding to the type-key operated. The impulse which the operating crank thus receives is also transmitted to the universal bar 57 that serves to actuate the escapement mechanism for the punching-machine-carriage. A full escapement actuating oscillation of said universal bar 57 is completed as the push-wire is caused to be retracted by the de-energizing of the solenoid 84 through 105 release of the type-key lever 91. The full oscillation of the universal bar 57 thus effected causes a corresponding oscillation of the escapement dogs 44 and 56 with a corresponding advance to the next denomination of the punching-machine-carriage 110 115 under the pull of its spring motor 43. Thus at each operation of a type-key a corresponding punch is selected and the punching-machine-carriage is caused to advance to the next denomination, all substantially in the 120 125 130

manner as heretofore practised. The punching-machine-carriage advances, of course, in unison with the step-by-step movements of the typewriter carriage, said latter movements being effected by means of the usual typewriter escapement mechanism upon operation of the type-keys.

- The type-key operation and step-by-step movements in both carriages may take place
- 10 after both carriages have been denominationaly positioned by operation of the typewriter tabulating keys 26. The operation of the invention in connection with said tabulating keys may be summarized as follows.
- 15 Depression of any tabulating key 26 elevates the corresponding denominational stop 28 of the typing mechanism and through the medium of the universal bar 125, actuatable by any stop 28, releases the typewriter carriage
- 20 from its escapement device, and thereby causes it to advance under the influence of its usual spring motor 25. Actuation of the universal bar 125 thus effected also closes the contact switch 129, thereby energizing
- 25 the solenoid 120 and delivering the thrust thereof to the switching carriage 99 by means of the push-wire 122, rod 117, and bell-crank 118. The solenoid 120 is thus energized before the stroke of a tabulating key 26 has
- 30 closed the contact switch 94 corresponding to said key 26. Even though said contact switch 94 is closed the corresponding solenoid 84 cannot, in the preferred arrangement, be energized until the switching carriage
- 35 99 has reached its tabulating position in which the plungers 97 connect the operating trains 83 with the tabulator-actuating-rods 104. As the switching carriage 99 reaches its tabulating position it closes the
- 40 contacts 137 and completes the circuit partially closed by the contacts 94, and thereby enables the solenoid 84 to be energized at the proper time. Upon a solenoid 84 being thus energized by operation of a tabulating key
- 45 26, it will be seen that a corresponding tabulator-actuating-rod 104 is displaced endwise with the consequent endwise displacement and latching of a corresponding denominational stop 67 for the punching-machine-
- 50 carriage. The endwise displacement of the tabulator-actuating-rod 104 also causes the withdrawal of the escapement dog 44 from the escapement wheel 42, whereupon the punching-machine-carriage impelled by its
- 55 spring motor 43 advances in a tabulating movement. The dog 44 is thus withdrawn or lifted through the medium of the universal bail 142, its shaft 144, the hook 148 and the dog-lifting lever 60.
- 60 The punching-machine-carriage now under way in a tabulating movement proceeds until the selected denominational stop 67 encounters the first zone-stop 68. As a result of said encounter the bail 81 is dis-
- 65 placed, causing the selected denominational

stop to be unlatched and retracted, and causing the switching carriage 99 to be restored to its normal position in which it is again effective to connect the operating trains with the punch-selecting bell-cranks. The displacement of the bail 81 also releases the dog 44 by causing the latch 64, which served to hold it, to be kicked off through the medium of arms 162 and 163 actuated by said bail 81 through the link 164. In this manner, through the encounter of a denominational stop 67 and zone-stop 68, a tabulating movement of the punching carriage is terminated, and the parts which were set and latched by operation of the tabulating key 26 are caused to be restored to their normal positions.

It will be understood that the means whereby the punching-machine-carriage escapement-mechanism is rendered ineffective in a units or last column position of the carriage also become effective as said carriage is brought to said position by operation of a tabulating key 26, as distinguished from arriving at said position through the regular step-by-step feeding movements of said carriage.

The twelve operating trains for the twelve hole positions herein shown, should be enough to serve for tabulating within all but exceptionally large ranges of denominations. In the illustration of the invention herein shown, only nine of said trains are employed for denominational tabulating; that is to say, nine denominational stops 67, each employing an operating train, are indicated, it being understood that the number of stops 67 and corresponding parts may be increased to the number of operating trains available, or may be less than the number herein shown. A number of denominational stops 67 greater than the number of operating trains 83 available may be provided for by supplying an operating train for each extra denominational stop 67, each extra operating train being, of course, actuated by its own tabulating key.

Figure 14 indicates how the solenoids 84 and 120, the several contacts 92 and 94 controlling the solenoids 84, and the contacts 129 for the solenoid 120 are connected. Figure 14 also shows the disposition of the contacts 137, actuated by the switching-carriage 99, in the scheme of connections. All of the solenoids are connected to a common lead embodied in wires 185, 186 and 187, said common lead being connected to one side of the source of current 86. Similarly one side of each of the several pairs of contacts is connected to a common lead connected to the other side of the current source 86, said latter common lead including the wires 138, 188 and 189. Said wire 138 normally open by reason of the contacts 137 is connected to a plate 190, which may form a common terminal for the several pairs of contacts 94, one of each pair of contacts forming part of said plate 190. Simi-

larly a plate 191 may form a common terminal for each of the pairs of contacts 92. The individual elements 90 of the contacts 92 may be mounted on the plate 191 and insulated from one another and from said plate 191, and are connected by individual wires 192 and 193 to their respective solenoids. The wires 192 for solenoids which are operated by the tabulating keys 26, are extended and connected to the individual elements 93 of the tabulating key contacts 94. Said individual elements 93, as indicated in Figure 14, are mounted on the plate 190 and insulated from said plate 190 and from one another. By means of wires 195, which form the extensions of the wires 192, said individual elements 93 of the contacts 94 may be connected to the wires 193 of their respective solenoids. The individual element 130 of the contacts 129 for the solenoid 120 not connected to the common lead is connected by a wire 196 to said solenoid 120. It will be understood that the arrangement or, in other words, the grouping or disposition of the wiring, may vary from the description here given without departing from the scheme of connections, said description following the conventional diagram indicated in Figure 14. All wires passing from the typing mechanism to the punching-mechanism may be gathered in a cable 103, Figure 2, which may be of suitable length to permit any desired relative disposition of said mechanism. Each tabulating key lever 27 may close its contacts 94 by means of an insulating stud 108 projecting from said lever and capable of engaging the individual contact element 93. An insulated stem 109 projecting upwardly from each individual contact element 90 of the type-key contacts may be engaged by the corresponding type-key lever 91.

As already stated, only the ten numeral keys are shown as being effective to actuate the solenoids 84. It will be understood that the invention may be applied to machines where the usual alphabet keys of the typewriter also actuate said solenoids 84, the actuation of some alphabet keys represented by two or more holes, requiring a corresponding actuation of two or more solenoids 84, in which case a contact switch for each solenoid operated by an alphabet key is closed. The present invention may be practised irrespective of whether the numeral keys alone, or both numeral and alphabet keys, are capable of actuating the solenoids 84 for selection of corresponding punches.

It will be noted that a denominational tabulating mechanism for the punching-machine-carriage may, according to the present invention, be provided without encumbering the punching-machine-carriage with additional operating trains, the same trains that serve the punch-selecting-mechanism also serving for the tabulating mechanism.

Variations may be resorted to within the scope of the invention, and portions of the improvements may be used without others.

Having thus described our invention, we claim:

1. In a combined typewriting and card-punching machine, the combination with typewriter-mechanism having a carriage and a step-by-step letter-feeding device therefor, punching mechanism including a punch-selecting device, a denomination-determining carriage and a step-by-step feeding device therefor, and means including a series of operating trains, whereby both mechanisms including both carriage-feeding devices may be jointly operated to type upon a work-sheet and produce a correspondingly punched record, of denominational tabulating mechanism effective upon both carriages to shift the same to similar or dissentaneous extents depending upon the extents and locations of corresponding zones in which said carriages operate, said tabulating mechanism including a single set of denominational tabulating keys, sets of corresponding denominational stops, one set for each carriage, means enabling said tabulating keys to actuate said operating trains, means under the control of said tabulating keys to transfer said trains from engagement with the punch-selecting device to select denominational stops for the punch-carriage, means, effective upon operation of any tabulating key, to initiate a tabulating movement of both carriages, and means including settable zone-stops for both carriages co-operative with the selected denominational stops, for terminating the tabulating movements of said carriages in predetermined zones and in the denomination corresponding to the tabulating key operated.

2. In a combined typewriting and card-punching machine, the combination with a set of keys, types operable by said keys, a carriage for typing, a step-by-step feeding mechanism therefor controlled by said keys, punches, punch-selecting devices, a movable denomination indexing carriage co-operative with said punch-selecting devices, and another step-by-step feeding mechanism for said second carriage, of operating trains from the type-keys to the punch-selecting devices, whereby operation of any key may actuate a corresponding punch-selecting device and also actuate said second feeding mechanism in accordance with the actuation of the typing carriage-feeding mechanism, denominational tabulating mechanism, including a set of denominational keys, for the typing carriage, a second denominational tabulating mechanism, including denominational devices selectively actuatable to tabulate the punching carriage denominational, and means, effective upon operation of the tabulating keys, enabling said operating trains to actuate the denominational tabulating mech-

anism for the punching-machine carriage in accordance with the corresponding operation of the typing carriage-tabulating mechanism, said means arranged so that the respective functions of said operating trains as punch-selecting mediums and tabulating mediums may be effected independently of one another.

3. In a combined typewriting and card-punching machine, the combination with a set of keys, types operable by said keys, a carriage for typing, a step-by-step feeding mechanism therefor controlled by said keys, punches, punch-selecting devices, a movable denomination indexing carriage co-operative with said punch-selecting devices, and another step-by-step feeding mechanism for said second carriage, of operating trains from the type-keys to the punch-selecting devices, whereby operation of any key may actuate a corresponding punch-selecting device and also actuate said second feeding mechanism in accordance with the actuation of the typing carriage-feeding mechanism, denominational tabulating mechanism, including a set of denominational keys, for the typing carriage, a second denominational tabulating mechanism, including denominational devices selectively actuatable to tabulate the punching carriage denominational, and means, effective upon operation of the tabulating keys, enabling said operating trains to actuate the denominational tabulating mechanism for the punching machine carriage in accordance with the corresponding operation of the typing carriage-tabulating mechanism, said means arranged so that either of the respective functions of said operating trains as punch-selecting mediums and tabulating mediums may be automatically effected, depending on whether a type-key or tabulating key is operated.

4. In a card-punching machine, the combination with punching devices including a set of selectively operable keys therefor, a movable denomination-determining carriage for said punching devices, a step-by-step feeding device for said carriage under the control of said keys and including a carriage-motor, of a denominational tabulating mechanism for said carriage including a set of denominational stops selectively movable into and out of effective positions, a corresponding set of denominational tabulating keys, individual stop-selecting trains, one from each denominational tabulating key to the corresponding stop, a counter-stopping device co-operative with a selected denominational stop to effect termination of a tabulating movement in a predetermined zone, means, effective upon the operation of any tabulating key, to release said carriage from the step-by-step feeding device to initiate a tabulating movement impelled by said motor, means whereby the ensuing reaction of the selected

denominational stop against said counter-stopping device causes termination of said release and terminates said tabulating movement, and additional means to prevent carriage-spacing by said step-by-step feeding device upon the carriage arriving at its lowest denominational position in each zone.

5. In a combined typewriting and card-punching machine, the combination with a typing mechanism having type-keys and a letter-feeding carriage co-operative therewith, and punching mechanism having punch-selecting devices and a step-by-step feeding denomination-indexing carriage co-operative therewith, of tabulating mechanism including a set of denominational keys for tabulating the typewriter-carriage denominational, tabulating mechanism, including a set of denominational members selectively actuatable, to tabulate the punching mechanism carriage denominational, a series of operating trains actuatable either by said type-keys or by said tabulating keys, and means whereby said trains, when actuated by the type-keys, are effective to actuate the punch-selecting devices, and whereby said trains, when actuated by the tabulating keys, are effective to actuate the tabulating mechanism for the punching mechanism carriage so that the punching mechanism carriage is, upon operation of any tabulating key, tabulated to a position corresponding to the position to which the typing carriage is tabulated by said operation.

6. In a combined typewriting and card-punching machine, the combination with type-keys, a letter-feeding carriage co-operative with said keys, and a punching mechanism including punch-selecting devices and a step-by-step feeding denomination indexing carriage co-operative with said punch-selecting devices, of denominational tabulating mechanism, including a set of denominational keys, for the typing carriage, denominational tabulating mechanism, including a set of selectively actuatable denominational indexing members, for the punching carriage, a set of punching mechanism operating trains actuatable either by said type-keys or by said tabulating keys, switching devices whereby said trains may be operatively connected to either the punch-selecting devices or to the denomination indexing tabulating members for the punching carriage, and means whereby said switching devices are caused to be conditioned so that said trains operate corresponding punch-selecting devices when the type-keys are operated, or are caused to be conditioned so that said trains operate corresponding denomination indexing tabulating members for the punching carriage when the tabulating keys are actuated.

7. In a combined typewriting and card-punching machine, the combination with

type-keys, a letter-feeding carriage co-operative with said keys, and punching mechanism including punch-selecting devices and a step-by-step feeding denomination indexing carriage co-operative with said punching selecting devices, of denominational tabulating mechanism, including a set of denominational tabulating keys, for the typing carriage, denominational tabulating mechanism, including a set of selectively actuatable denomination indexing members for the punching carriage, punching mechanism operating trains actuatable either by the type-keys or by the tabulating keys, a set of interponents capable of connecting said trains either with corresponding punch-selecting devices or with corresponding denomination indexing members for the punching carriage, and means for conditioning said interponents according to operation of type-keys or tabulating keys so that in the operation of said type-keys corresponding punch-selecting devices are actuated, or so that in the operation of said tabulating keys corresponding denomination determining members for the punching carriage are actuated.

8. In a combined typewriting and card-punching machine, the combination with type-keys, a letter-feeding carriage co-operative with said keys, and punching mechanism including punch-selecting devices and a step-by-step feeding denomination indexing carriage co-operative with said punching selecting devices, of denominational tabulating mechanism, including a set of denominational tabulating keys, for the typing carriage, denominational tabulating mechanism, including a set of selectively actuatable denomination determining members, for the punching carriage, punching mechanism operating trains actuatable either by the type-keys or by the tabulating keys, a set of shiftable interponents normally connecting said trains with corresponding punch-selecting devices so that in the operation of said type-keys corresponding punch-selecting devices are actuated, and means effective upon the operation of the tabulating keys, for shifting said interponents, thereby enabling the trains when actuated by said tabulating keys to select corresponding denomination determining tabulating members for the punching carriage.

9. In a combined typewriting and card-punching machine, the combination with type-keys, a letter-feeding carriage co-operative with said keys, and punching mechanism including punch-selecting devices and a step-by-step feeding denomination indexing carriage co-operative with said punching selecting devices, of denominational tabulating mechanism, including a set of denominational tabulating keys, for the typing carriage, denominational tabulating mechanism, including a set of selectively actuatable denomination in-

dexing members, for the punching carriage, punching mechanism operating trains, each train including an electromagnet for effecting the actuation of said each train, a normally open energizing circuit for each magnet, each train also including means operable either by a corresponding type-key or by a corresponding denominational tabulating key for closing said circuit, switching devices whereby said trains may be operatively connected to either the punch-selecting devices or to the denomination indexing tabulating members for the punching carriage, and means whereby said switching devices are caused to be conditioned so that in the operation of said trains by the type-keys corresponding punch-selecting devices are operated or are caused to be conditioned, so that in the operation of said trains by said tabulating keys corresponding denomination indexing tabulating members for the punching mechanism carriage are actuated.

10. In a combined typewriting and card-punching machine, the combination with types, type-keys, punching elements arranged in numerous denominational columns, each column including a series of punching elements, a series of punch-selecting devices corresponding to the several punching elements of a column, and a denomination-determining carriage carrying said punch-selecting devices and feedable from column to column upon the actuation of said punch-selecting devices, of operating trains, one for each of the several punch-selecting devices on said carriage, said trains selectively operable by individual type-keys to effect actuation of corresponding punch-selecting devices, denominational tabulating mechanism for said carriage, said mechanism including a series of denominational tabulating keys, a series of corresponding denominational stops individually movable into effective position, means enabling the denominational tabulating keys to actuate said operating trains, means whereby upon the operation of any tabulating key the corresponding operating train is enabled to effect the selection of a corresponding denominational stop without being effective upon a punch-selecting device, and means effective upon the operation of any tabulating key for effecting a tabulating movement of said carriage according to the stop selected.

11. In a card-perforating machine, the combination with punching elements arranged in numerous denominational columns, each column including a series of punching elements, a series of punch-selecting devices corresponding to the several punching elements of a column, and a denomination-determining carriage for said punch-selecting devices and feedable from column to column upon the actuation of the punch-selecting devices, of operating trains,

- one for each of the several punch-selecting devices on said carriage and effective to actuate said punch-selecting device, means including a set of keys for selectively operating 5 said trains, denominational tabulating mechanism for said carriage, said mechanism including a series of denominational tabulating keys, a series of corresponding denominational stops selectively movable into effective 10 position, means enabling the denominational tabulating keys to actuate said operating trains, means whereby upon operation of any tabulating key the corresponding operating train is enabled to effect the selection of a 15 corresponding denominational stop without being effective upon a punch-selecting device, and means effective upon the operation of any tabulating key for effecting a tabulating movement of said carriage according to the 20 stop selected.
12. In a card-perforating machine for punching a card of the character herein described, said card divided into zones, each zone having numerous denominational columns of hole-spaces, the combination with a series of punching devices corresponding to the hole-spaces of a card column, and a denomination indexing carriage carrying said punching devices, of operating trains, one for 25 each of said punching devices and effective to actuate the latter, a set of keys for selectively operating said trains, denominational tabulating mechanism for said carriage, said mechanism including a series of denominational tabulating keys, a series of corresponding denominational stops selectively movable into effective position, means enabling the denominational tabulating keys to actuate 30 said operating trains, means whereby upon operation of any tabulating key the corresponding operating train is enabled to effect the selection of a corresponding denominational stop without being effective upon a punch-selecting device, and means effective upon the operation of any tabulating key for effecting a tabulating movement of said carriage according to the stop selected.
13. In a card-perforating machine, the combination with a series of individually-operable punch-selecting devices, and a denomination indexing carriage carrying said punch-selecting devices, of a stationary set of keys corresponding to the several punch-selecting devices, a series of operating trains 35 actuable by said keys and effective upon the punch-selecting devices, denominational tabulating mechanism for said carriage, said mechanism including a series of denominational tabulating keys, a series of corresponding denominational stops selectively movable into effective position, means enabling the denominational tabulating keys to actuate 40 said operating trains, means whereby upon operation of any tabulating key the corresponding operating train is enabled to effect the selection of a corresponding denominational stop without being effective upon a punch-selecting device, and means effective upon the operation of any tabulating key for effecting a tabulating movement of said carriage according to the stop selected.
14. In a card-perforating machine, the combination of a punch-selecting device, a denomination indexing carriage carrying said punch-selecting device, a key, an operating train connecting said key and punch-selecting device, a tabulating mechanism for said carriage, said mechanism including a tabulating key, carriage-stopping means movable into effective position, means enabling said tabulating key to actuate said operating train, and means whereby, upon the operation of the tabulating key, said train, besides being actuated thereby, is automatically enabled to move said carriage-stopping 50 means into effective position without being effective upon the punch-selecting device, and means, effective upon the operation of said tabulating key, for initiating a tabulating movement and then terminating said movement by means of said carriage-stopping means.
15. In a card-perforating machine, the combination with a series of individually-operable punch-selecting devices, and a denomination indexing carriage carrying said punch-selecting devices, of a stationary set of keys corresponding to the several punch-selecting devices, a set of electromagnets, each magnet including a member actuatable thereby, one magnet for each punch-selecting device, means enabling said keys, when operated, to energize corresponding electromagnets, means operatively connecting said actuatable members of the several magnets to corresponding punch-selecting devices, a denominational tabulating mechanism for said carriage, said mechanism including a set of denominational tabulating keys and a corresponding set of denominational stops individually movable into effective position and carried by said carriage, means enabling said tabulating keys, when operated, to energize said electromagnets, means whereby the aforesaid connecting means, when actuated by their respective magnets through operation of said tabulating keys, are effective for selectively moving said denominational stops into effective position according to the tabulating keys operated, and means called into action by the operation of any tabulating key to effect a tabulating movement of said carriage according to the stop selected.
16. In a card-perforating machine, the combination with a series of individually-operable punch-selecting devices, and a step-by-step feeding denomination indexing carriage cooperative with said punch-selecting devices, of a set of keys corresponding to the several punch-selecting devices, denomina- 130

5 tional tabulating mechanism for said carriage including a set of denominational tabulating keys and a set of corresponding denominational stops individually movable into effective position, a plurality of electromagnets, means enabling said magnets to be selectively energized either by operation of the keys corresponding to the punch-selecting devices or by operation of the tabulating keys, and
10 10 means whereby said magnets, when energized by operation of the keys corresponding to the punch-selecting devices, are enabled to actuate corresponding punch-selecting devices, and whereby said magnets, when energized
15 15 by operation of the tabulating keys, are enabled to select and move into effective position corresponding denominational tabulating stops.

17. In a card-perforating machine, the
20 combination with a series of individually operable punch-selecting devices, and a step-by-step feeding denomination indexing carriage cooperative with said punch-selecting devices, of a set of keys corresponding to the
25 several punch-selecting devices, denominational tabulating mechanism for said carriage including a set of denominational tabulating keys and a set of corresponding denominational stops individually movable into effective position, a plurality of electromagnets, means enabling said magnets to be selectively energized either by operation of the keys corresponding to the punch-selecting devices or by operation of the tabulating keys, means
30 30 whereby said magnets, when energized by operation of the keys corresponding to the punch-selecting devices, are enabled to actuate corresponding punch-selecting devices, and whereby said magnets, when energized
35 35 by operation of the tabulating keys, are enabled to select and move into effective position corresponding denominational tabulating stops, and means effective upon the operation of any tabulating key to initiate a tabulating movement of said carriage and then terminate said movement according to the
40 40 stop selected.

18. In a card-perforating machine, the
50 combination with a series of individually operable punch-selecting devices, and a step-by-step feeding denomination indexing carriage co-operative with and carrying said punch-selecting devices, of a stationary set of keys corresponding to the several punch-selecting devices, a denominational tabulating mechanism for said carriage including a set of denominational tabulating stops carried thereby and individually movable into effective position, a stationary set of tabulating keys corresponding to said denominational stops, and a series of operating trains actuatable by either set of keys and effective upon either the punch-selecting devices or the denominational tabulating stops, depending on which set of keys is operated.

19. In a card-perforating machine, the combination with a series of individually operable punch-selecting devices, and a step-by-step feeding denomination indexing carriage cooperative with and carrying said punch-selecting devices, of a stationary set of keys corresponding to the several punch-selecting devices, a denominational tabulating mechanism for said carriage including a set of denominational tabulating stops carried thereby and individually movable into effective position, a stationary set of tabulating keys corresponding to said denominational stops, and a series of operating trains actuatable by either set of keys and effective upon either the punch-selecting devices or the denominational tabulating stops, depending on which set of keys is operated, said trains including devices for being thus effective without impeding the movements of said carriage. 85

20. In a card-perforating machine, the combination with a series of individually operable punch-selecting devices, and a step-by-step feeding denomination indexing carriage, cooperative with and carrying said punch-selecting devices, of a stationary set of keys corresponding to the several punch-selecting devices, a denominational tabulating mechanism for said carriage including a set of denominational tabulating stops carried thereby and individually movable into effective position, a stationary set of tabulating keys corresponding to said denominational stops, a series of actuators operatively attached to said carriage; said actuators flexible or yieldable to permit free carriage movement, means whereby said actuators may be operated by either set of keys, and means whereby said actuators are effective upon either the punch-selecting devices or the denominational tabulating stops, depending on which set of keys is operated. 100

21. In a card-perforating machine, the combination with a series of individually operable punch-selecting devices, and a step-by-step feeding denomination indexing carriage, cooperative with and carrying said punch-selecting devices, of a stationary set of keys corresponding to the several punch-selecting devices, a denominational tabulating mechanism for said carriage including a set of denominational tabulating stops carried thereby and individually movable into effective position, a stationary set of tabulating keys corresponding to said denominational stops, a series of flexible actuating wires operatively attached to said carriage, said wires being flexible to permit free carriage movement, means whereby said wires may be actuated by either set of keys, and means whereby either the punch-selecting devices or denominational stops are actuated by said wires, depending on which set of keys is operated. 115

22. In a card-perforating machine, the combination with a series of independently 120

- operable punch-selecting devices, and a step-by-step feeding denomination indexing carriage cooperative therewith, of a set of keys corresponding to the several punch-selecting devices, a series of operating trains normally effective to connect said keys and punch-selecting devices, a denominational tabulating mechanism for said carriage including a set of denominational stops individually movable into effective position, a set of tabulating keys corresponding to said stops, conditioning means, actuatable by the operation of any tabulating key, for rendering said trains effective for the selection of denominational stops, and means, dependent upon a completed actuation of said conditioning means, whereby the operation of said tabulating key actuates a corresponding train to effect selection of a corresponding denominational stop.
23. In a card-perforating machine, the combination with a series of independently operable punch-selecting devices, and a step-by-step feeding denomination indexing carriage cooperative therewith, of a set of keys corresponding to the several punch-selecting devices, a series of operating trains normally effective to connect said keys and punch-selecting devices, a denominational tabulating mechanism for said carriage including a set of denominational stops individually movable into effective position, a set of tabulating keys corresponding to said stops, a train-switching device actuatable by the operation of any tabulating key for rendering said trains effective for the selection of denominational stops, and means, dependent upon a completed actuation of said train-switching device, whereby the operation of said tabulating key actuates a corresponding train to effect selection of a corresponding denominational stop.
24. In a card-perforating machine, the combination with a series of independently operable punch-selecting devices, and a step-by-step feeding denomination indexing carriage cooperative therewith, of a set of keys corresponding to the several punch-selecting devices, a denominational tabulating mechanism for said carriage including a set of denominational stops individually movable into effective position, a set of tabulating keys corresponding to said stops, a series of operating trains operable by the keys for the punch-selecting devices, a shiftable set of interponents normally connecting said trains and punch-selecting devices, means actuatable by the operation of any tabulating key for shifting said interponents to thereby render said trainseffective for the selection of denominational stops, and means, dependent upon a completed shifting of said interponents, whereby the operation of said tabulating key actuates a corresponding train to effect selection of a corresponding denominational stop.
25. In a card-perforating machine, the combination with a series of independently operable punch-selecting devices, and a step-by-step feeding denomination indexing carriage cooperative therewith, of a set of keys corresponding to the several punch-selecting devices, a series of electrically actuatable trains controlled by key contacts and normally effective for enabling said keys to actuate corresponding punch-selecting devices, a denominational tabulating mechanism for said carriage including a set of denominational stops individually movable into effective position, a set of tabulating keys corresponding to said stops, conditioning means, actuatable by the operation of any tabulating key, for rendering said trainseffective for the selection of denominational stops, tabulating key contacts provided for the operation of said electrically actuatable trains by said tabulating keys, and a contact device controlled by said conditioning means for rendering the tabulating key contacts effective only through a completed actuation of said conditioning means.
26. In a combined typewriting and card-perforating machine, the combination with a typing carriage and a punching-carriage, said carriages urged in a feeding direction by individual motors and controlled by individual step-by-step feeding devices, of tabulating mechanism under the control of a single key-device, for tabulating both carriages in corresponding zones, said mechanism including a stop device for the typing carriage and rendered effective by operating said key-device, a carriage releasing device co-operative with said stop device for releasing the typing carriage for an ensuing tabulating movement, said stop device being held effective by sustained action upon said key-device until the tabulating carriage movement is arrested thereby, means for releasing the punching carriage from the control of its feeding device for an immediately ensuing tabulating movement concomitantly with the stroke of the key-device that actuates the typing-carriage stop device, and means operative independently of said key device for automatically preventing further punching-carriage movement at the end of each zone.
27. In a tabulating mechanism for a punching-machine carriage, or the like, the combination with a step-by-step feeding device controlling said carriage, said device including a member displaceable to effect release of the carriage from the control of said device for an immediately ensuing denominational tabulating movement, of means operable to displace and latch said member to initiate said movement, said means having provision for permitting immediate restoration of said member in order that short tabulating runs of said carriage may be terminated, and additional means for preventing spacing of the carriage beyond the position of lowest denomination.

28. In a tabulating mechanism for a punching-machine carriage, or the like, the combination with a step-by-step feeding device controlling said carriage, said device including a member displaceable to effect release of the carriage from the control of said device for an immediately ensuing tabulating movement, of means operable to displace and latch said member to initiate said movement, a tabulating stop device effective to cause the unlatching and restoration of said member to thereby terminate a tabulating movement, said member displacing and latching means having provision for permitting immediate restoration of said member in order that short tabulating runs as determined by said stop device may be effectively terminated, and additional means for preventing spacing of the carriage beyond the place corresponding to the lowest denomination.

29. The combination with a punching-machine carriage, or the like, and a step-by-step feeding mechanism therefor, of a device defining different zones in the carriage travel, and means co-operating with said device for automatically rendering said step-by-step feeding mechanism inoperative at the position in each zone corresponding with the last possible punching position therein.

30. The combination with a punching-machine carriage, or the like, and key actuated mechanism co-operative with said carriage and including step-by-step carriage feeding means normally actuatable for advancing said carriage at each key operation, of a device defining different zones in the carriage travel, and means co-operating with said zoning device for automatically rendering said step-by-step feeding means inoperative at the position in each zone corresponding with the last possible punching position therein.

31. The combination with a punching-machine carriage, or the like, and key actuated mechanism co-operative with said carriage and including step-by-step carriage feeding means normally actuatable for advancing said carriage at each key operation, of a device defining different zones in the carriage travel, means co-operating with said zoning device for automatically rendering said step-by-step feeding means inoperative at the position in each zone corresponding with the last possible punching position therein, and means for advancing said carriage at will beyond said positions to thereby render said feeding means operative again.

32. The combination with a punching-machine carriage, or the like, and key actuated mechanism co-operative with said carriage and including step-by-step carriage feeding means normally actuatable for advancing said carriage at each key operation, of a denominational tabulating mechanism for said carriage including a series of denominational stops

and co-operating zone-stops, and means controlled by said zone-stops during the carriage travel for rendering the carriage feeding means inoperative by said keys as the carriage reaches the units or last column position of a zone, so that the denominational stop for the highest denomination of the following zone may not escape relatively to the zone-stop for said following zone.

33. The combination with a punching-machine carriage, or the like, and key actuated mechanism co-operative with said carriage and including step-by-step carriage feeding means normally actuatable for advancing said carriage at each key operation, of a denominational tabulating mechanism for said carriage including a series of denominational stops and co-operating zone-stops, and means controlled by said zone-stops during the carriage travel for rendering the carriage feeding means inoperative by said keys as the carriage reaches the units or last column position of a zone, so that the denominational stop for the highest denomination of the following zone may not escape relatively to the zone-stop for said following zone, said means having provision so that said carriage feeding means become operative again through a subsequent actuation of said tabulating mechanism.

34. The combination with a typewriter having a set of type-keys, a letter-feeding carriage and denomination tabulating mechanism therefor including a set of denominational tabulating keys, and a card-perforator, separate from said typewriter, having a series of punch-selecting devices and a denomination indexing carriage co-operative with said latter devices, of denominational tabulating mechanism for the perforator carriage, a series of electrically actuatable trains operable by either the type-keys or tabulating keys and projected from said keys toward the card-perforator, and means, dependent on which set of keys is operated, whereby said trains are effective to operate either the perforator punch-selecting devices concomitantly with the type-key operation, or are effective to operate the perforator-carriage-tabulating mechanism concomitantly and in accordance with the tabulating of the typewriter carriage.

35. The combination with a typewriter having a set of type-keys, a letter-feeding carriage and denomination tabulating mechanism therefor including a set of denominational tabulating keys, and a card-perforator, separate from said typewriter, having a series of punch-selecting devices and a denomination indexing carriage co-operative with said latter devices, of denominational tabulating mechanism for the perforator carriage, a series of electrically-actuable trains operable by either the type-keys or tabulating keys and projected from said keys toward the card-

- perforator, and means, dependent on which single bank of denominational keys and letter-keys to control the movements of said carriages, and punch-selectors for said device, of denominational tabulating selectors, stops engaging the same to intermit the movement 70 of the device-carriage and stop the same at predetermined stations, actuating trains for the card-punching device responsive to certain of said keys, and means responsive to said denominational keys to transfer the 75 actuating trains from normal position, wherein they may engage with the punch-selectors, into position to engage with the denominational tabulating selectors.
39. In a combined typewriting machine 80 and card-punching device, the combination with a machine-carriage, a device-carriage, a single bank of denominational keys and letter-keys to control the movements of said carriages, and punch-selectors for said device, of denominational tabulating selectors, stops engaging the same to intermit the movement of the device-carriage and stop the same at predetermined stations, actuating 85 trains for the card-punching device responsive to certain of said keys, means responsive to said denominational keys to transfer the actuating trains from normal position, wherein they may engage with the punch-selectors, into position to engage with the denominational tabulating selectors, and means actuated by said trains to initiate a 90 movement of the device-carriage.
40. In a combined typewriting machine 100 and card-punching device, the combination with a machine-carriage, a device-carriage, a single bank of denominational keys and letter-keys to control the movements of said carriages, and punch-selectors for said device, of denominational tabulating selectors, stops engaging the same to intermit the movement of the device-carriage and stop the same at predetermined stations, actuating 105 trains for the card-punching device responsive to certain of said keys, means responsive to said denominational keys to transfer the actuating trains from normal position, wherein they may engage with the punch-selectors, into position to engage with the denominational tabulating selectors, and means actuated by said trains to initiate a 110 movement of the device-carriage, and means to restore the parts to their initial position upon the device-carriage moving to each of said predetermined stations.
41. In a combined typewriting machine 115 and card-punching device, the combination with a machine-carriage, a device-carriage, denominational keys and letter-keys controlling the movements of both carriages, and punch-selectors for said device, of denominational tabulating selectors to stop the movement of the device-carriage at predetermined stations, actuating trains controlled 120 selectively by said denominational keys, and 125
36. The combination with a typewriter having a set of type-keys, and a card-perforator, separate from said typewriter, having a series of punch-selecting devices and a de- 20 nomination-indexing carriage co-operative with said latter devices, of denominational tabulating mechanism for said carriage, a set of denominational tabulating keys disposed at or sufficiently near the typewriter 25 for operation in conjunction with the type-keys, a series of electrically-actuable trains operable by either the type-keys or tabulating keys and projected from said keys toward the perforator, and means, dependent 30 on which set of keys is operated, whereby said trains are effective to operate either the punch-selecting devices concomitantly and in accordance with the type-key operation, or are effective to actuate the perforator-car- 35 riage-tabulating mechanism.
37. The combination with a typewriter having a set of type-keys, and a card-perforator, separate from said typewriter, having a series of punch-selecting devices and a de- 40 nomination-indexing carriage co-operative with said latter devices, of denominational tabulating mechanism for said carriage, a set of denominational tabulating keys disposed at or sufficiently near the typewriter for operation in conjunction with the type-keys, a series of electrically-actuable trains operable by either the type-keys or tabulating keys and projected from said keys toward the perforator, and means, dependent on which 45 set of keys is operated, whereby said trains are effective to operate either the punch-selecting devices concomitantly and in accordance with the type-key operation, or are effective to actuate the perforator-carriage-tabulating mechanism, said trains including an electric cable constituting circuit-forming connections controlled by said keys, whereby said trains are projected as aforesaid to join the typewriter and perforator, said connec- 50 tions being common to the punch-selecting devices and the perforator-carriage-tabulating devices.
38. In a combined typewriting machine and card-punching device, the combination 60 with a machine-carriage, a device-carriage, a 65

means actuated by the denominational keys to first shift the actuating trains from possible engagement with the punch-selectors to operable engagement with said denominational tabulating selectors and then set said tabulating selectors to stop the device-carriage at predetermined stations.

42. In a combined typewriting machine and card-punching device, the combination 10 with a machine-carriage, a device-carriage, denominational keys and letter-keys controlling the movements of both carriages, and punch-selectors for said device, of denominational tabulating selectors to stop the 15 movement of the device-carriage at predetermined stations, actuating trains controlled selectively by said denominational keys, transfer means responsive to said denominational keys to shift the actuating trains into 20 position for engagement with said denominational tabulating selectors, and a detent to retain the transfer means in shifted position.

43. In a combined typewriting machine 25 and card-punching device, the combination with a machine-carriage, a device-carriage, denominational keys and letter-keys controlling the movements of both carriages, and punch-selectors for said device, of denominational tabulating selectors to stop the 30 movement of the device-carriage at predetermined stations, actuating trains controlled selectively by said denominational keys, transfer means responsive to said denominational keys to shift the actuating trains into 35 position for engagement with said denominational tabulating selectors, a detent to retain the transfer means in shifted position, and restoring means to release said detent 40 and permit the transfer means to move to its initial position at the termination of the predetermined movement of the device-carriage at each of said stations.

44. In a combined typewriting machine 45 and card-punching device, the combination with a machine-carriage, a device-carriage, denominational keys and letter-keys controlling the movements of both carriages, and punch-selectors for said device, of denominational tabulating selectors to stop the 50 movement of the device-carriage at predetermined stations, actuating trains controlled selectively by said keys, transfer means responsive to said denominational keys to shift the actuating trains into engagement with said denominational tabulating selectors, a detent to retain the transfer means in shifted position, and means to restore said transfer means 55 automatically to its initial position.

60 45. In a combined typewriting machine and card-punching device, the combination with a machine-carriage, a device-carriage, denominational keys and letter-keys controlling the movements of both carriages, and 65 punch-selectors for said device, of denomina-

tional tabulating selectors to stop the movement of the device-carriage at predetermined stations, actuating trains controlled selectively by said denominational keys, transfer means responsive to said denominational keys to engage said trains with the denominational tabulating selectors, and means to connect the denominational keys with said trains when the transfer means has moved to its extreme shifted position.

70 46. In a combined typewriting machine and card-punching device, the combination with a machine-carriage, a device-carriage, denominational keys and letter-keys controlling the movements of both carriages, and punch-selectors for said device, of denominational tabulating selectors to stop the movement of the device-carriage at predetermined stations, actuating trains controlled selectively 75 by said keys, means responsive to said denominational keys to shift the actuating trains into operable engagement with said denominational tabulating selectors, means actuated by said trains to initiate a movement 80 of the punch-device-carriage, and means responsive to said denominational keys to terminate said movement of the device-carriage immediately following its initiation and to start said movement again to allow the device-carriage to move under the control of the denominational tabulating selectors to the proximate predetermined station.

85 47. In a combined typewriting machine and card-punching device, the combination 90 with a machine-carriage, a device-carriage, denominational keys and letter-keys controlling the movements of both carriages, and punch-selectors for said device, of denominational tabulating selectors to stop the movement of the device-carriage at predetermined 95 stations, actuating trains controlled selectively by said keys, transfer means responsive to said denominational keys to shift the actuating trains into engagement with said denominational tabulating selectors, means actuated by said trains to initiate a movement 100 of the punch-device-carriage, means responsive to said denominational keys to terminate said movement of the punch-device-carriage immediately following its initiation and to 105 permit said movement to start again to allow said device-carriage to move under the control of the denominational tabulating selectors to the next following predetermined station, and a device to silence the last-named 110 means upon the device-carriage reaching a units denomination station.

115 48. In a combined typewriting machine and card-punching device, the combination 120 with a machine-carriage, a device-carriage, denominational keys and letter-keys controlling the movements of both carriages, and punch-selectors for said device, of denominational tabulating selectors to stop the movement of the device-carriage at predetermined 125 stations.

stations, actuating trains controlled selectively by said denominational keys, transfer means responsive to said denominational keys to shift the actuating trains into operative engagement with said denominational tabulating selectors, a detent to retain the transfer means in shifted position, and means to restore said transfer means to its initial position upon the punch-device-carriage arriving at any predetermined station.

49. A combined typewriter and perforator controlled from a single keyboard, having main and denominational keys, a typewriter-carriage and a perforator-carriage, a series of denominational tabulating selectors responsive to said denominational keys, and a series of pre-settable zone-tabulating stops to engage said selectors to stop the carriages for controlling the tabulating movement of the same, actuating trains responsive to said main keys, and a transfer mechanism responsive to the denominational keys to engage the trains with said tabulating selectors.

50. In a card-perforating machine for keyboard-control, the combination with punches, a set of punch-selectors, a carriage, a set of denominational tabulating selectors, a pre-settable series of stationary zone-tabulating stops to engage said selectors to stop said carriage, a keyboard having keys, and actuating trains under control of the keys, of means to transfer said trains from operative engagement with one set of selectors to the other.

51. In a card-perforating machine for keyboard-control, the combination with a set of punches, a set of punch-selectors, a carriage, a set of denominational tabulating selectors on said carriage, a pre-settable series of stationary tabulating stops to engage said tabulating selectors to stop said carriage, a keyboard having main and auxiliary keys, and actuating trains under control of the main keys to govern the operation of the machine, of means controlled by the auxiliary keys to transfer said trains from operative engagement with one set of selectors to the other.

52. In a keyboard-controlled card-perforating machine, the combination with a set of punches, a set of punch-selectors, a carriage, a set of denominational tabulating selectors, a pre-settable set of stationary tabulating stops to engage said tabulating selectors to stop said carriage, and a keyboard having main and auxiliary keys, of trains for actuating certain of said selectors, and means for engaging said trains with one set of selectors or the other.

53. In a keyboard-controlled card-perforating machine, the combination with a set of punches, a set of punch-selectors, a carriage, a set of denominational tabulating selectors, a pre-settable set of stationary tabulating stops to engage said tabulating selec-

tors to stop said carriage, and a keyboard, of selector-actuating trains, and means for engaging said trains with one set of selectors or the other under the control of said keyboard.

54. A card-perforating machine having 70 punching instrumentalities, zone-determining means, means to locate possible perforations in selected denominational positions in zones predetermined on the card, punch-selecting keys normally disconnected from the denomination-selecting means, and means for connecting the punch-selecting keys to said denomination-selecting means. 75

55. In a combined typewriter and card-perforator, the combination with a typewriter-carriage, a perforator-carriage, and keys controlling the travel of both carriages in predetermined relation to each other, of denominational tabulating selectors, stops for 80 the same for each carriage to intermit the movement of the same to stop at predetermined stations, certain of said keys controlling both carriages for a step-by-step movement and other keys controlling the carriages 85 for dissentaneous movements, and means included in the perforator to delete one step-by-step movement of the perforator-carriage at the end of each dissentaneous movement.

56. In a combined typewriter and card-perforator, the combination with a typewriter-carriage, a perforator-carriage, and keys controlling the travel of each carriage in predetermined relation to each other, of actuating trains to control the movements 100 of the perforator responsive to certain of said keys, and means to operably engage said trains with all of the keys. 105

57. In a combined typewriter and card-perforator, the combination with a typewriter-carriage, a perforator-carriage, tabulating selectors for each carriage, and keys controlling the travel of each carriage in predetermined relation to each other by said 110 selectors, of key-operable normally disconnected actuating trains for the perforator, and means to connect said trains at will with all the keys to control their engagement with the tabulating selectors.

58. A card-punching mechanism, to record 115 data, by perforations in parallel zones in a card, having a set of punches, a set of punch-selectors, a movable carriage controlled thereby, means responsive to the punch-selectors to intermit the carriage-movement a fixed distance for each punching operation, a set of denominational tabulating selectors, means responsive to said tabulating selectors, to also intermit the movement of the carriage but 120 for various distances of travel according to the widths of the card-zones to receive the perforated data, and automatic means for disconnecting the punch-selectors from control of the carriage-movement upon the car- 125 130

riage reaching the end of each of the card-zones.

59. A keyboard-controlled card-punching mechanism, to record data, by perforations in parallel zones on a card, having a set of punches, a set of punch-selectors, a movable carriage, means responsive to the punch-selectors to intermit the carriage-movement a fixed distance for each punch-operation, a set of denominational tabulating selectors, means responsive to said tabulating selectors to also intermit the movement of the carriage but for various distances of travel according to the widths of the card-zones to receive the 15 perforated data, and means responsive to certain keys of the keyboard for transferring the control of the same from one set of selectors to the other.

60. A keyboard-controlled perforating machine for tabulating denominational data by perforations in a card in lateral zones, having a movable carriage, mechanism to intermit said movement for zone-tabulating, including a series of denominational tabulating 25 selectors supported by said carriage, a series of stationary pre-settable zone-stops to engage said selectors to stop the carriage, data-keys for reinstating said movement, and means controlled by said zone-stops to cause the data-keys to be effective for spacing the carriage at all positions of the carriage excepting those corresponding to the lowest denomination in each zone.

61. A keyboard-controlled perforating machine for tabulating denominational data by perforations in a card in lateral zones, having a movable carriage, mechanism to intermit said movement for zone-tabulating, including a series of denominational tabulating 35 selectors supported by said carriage, a series of pre-settable zone-stops to engage said selectors to stop the carriage, means controlled by the keyboard for normally reinstating said movement, means controlled by said zone-stops to cause the reinstating means to be effective for spacing the carriage at all positions of the carriage excepting those corresponding to the lowest denomination in each zone, and means controlled by the keyboard to restore the parts to their initial 50 positions.

62. A perforating machine for tabulating denominational data by perforating a card in lateral zones, a keyboard controlling the 55 machine, having a set of data-keys and a set of denominational tabulating keys, a movable carriage, mechanism to intermit the movement of the carriage for zone-tabulating, including a series of denominational tabulating 60 selectors supported by said carriage, a series of pre-settable zone-stops to engage said selectors to stop the carriage, means controlled by the keyboard for normally reinstating said movement, means controlled by said 65 zone-stops to cause the reinstating means to

be effective for spacing the carriage at all positions of the carriage excepting those corresponding to the lowest denomination in each zone, and means to restore the parts to their initial positions upon the operation of denominational keys.

63. In a keyboard-controlled perforating machine for tabulating denominational data by perforations in a card in lateral zones, the combination with a movable carriage, mechanism to intermit said movement for zone-tabulating, and means for giving the carriage a uniform step-by-step movement during data-recording, of a single actuating means 70 under control of the keyboard for selectively engaging said mechanism and the first-mentioned means.

64. A machine for perforating denominational data in a card, having a movable carriage, settable stops to intermit the carriage-travel for unequal increments, punch-selectors, a device actuated by the same to intermit the carriage-travel for equal increments, and mechanism engaging said stops to automatically prevent the feeding of the carriage 85 by said device at predetermined positions in the carriage-travel.

65. A machine for perforating denominational data in a card, having a movable carriage, settable stationary stops to intermit 90 the carriage-travel for unequal increments, punch-selectors, a device actuated by the same to intermit the carriage-travel for equal increments, and mechanism supported on said carriage, engaging said stops to automatically prevent the feeding of the carriage by said device at predetermined positions in the carriage-travel.

66. A machine for perforating denominational data in a card, having a movable carriage, settable stops to intermit the carriage-travel for unequal increments, punch-selectors, a device actuated by the same to intermit the carriage-travel for equal increments, and mechanism engaging said stops to automatically prevent the feeding of the carriage by said device at predetermined positions in the carriage-travel representing data of the lowest denomination.

67. A card-perforating machine having punching instrumentalities, selecting means to locate possible perforations by the same in predetermined zones on the card, keys to control the same, additional punch-selecting keys normally disconnected from said selecting means, to determine the punches to be operated, and a transfer device under the control of the first-mentioned keys to connect the punch-selecting keys to said selecting means.

FRANK K. DAVIS.
CHARLES C. TAYLOR.
